(57) **CLAIM**

We claim an ornamental design for a bottle, as shown and described.

DESCRIPTION

A portion of the disclosure of this patent document contains material which is subject to copyright protection. The copyright owner has no objection to the facsimile reproduction of the patent disclosure as it appears in the United States Patent and Trademark Office patent files or records, but otherwise reserves all copyright rights whatsoever.

FIG. 1 is a top perspective view of a bottle, showing our new design;

FIG. 2 is a right side view thereof;

FIG. 3 is a left side view thereof;

FIG. 4 is a front view thereof;

FIG. 5 is a rear view thereof;

FIG. 6 is a top plan view thereof; and,

FIG. 7 is a bottom plan view thereof.

It will be understood that the broken lines presented in the drawing are for illustration purposes only, and do not form a part of the claimed design. The broken lines represent parts of the article that form no part of the claimed design. The dot-dash lines represent the boundaries of the claim and form no part thereof.
